WELL TOOL

Herbert C. Otis, Dallas, Tex.

Application July 27, 1946, Serial No. 686,632

5 Claims. (Cl. 166—1)

1

This invention relates to new and useful improvements in well tools.

One object of the invention is to provide an improved well tool which is adapted to be removably positioned in a well flow conductor for use as a support or stop member for well devices.

An important object of the invention is to provide an improved well tool which is adapted to be lowered into the bore of a well flow conductor and anchored therein by expanding locking means into the recess at a coupling between the ends of adjacent sections of the flow conductor.

A further object of the invention is to provide an improved well tool of the character described having anchoring means which may be moved into anchoring engagement in the recess at a coupling in a well flow conductor and firmly held in such position to prevent downward movement of the well tool in the conductor, said tool being releasable and removable from the flow conductor.

Another object of the invention is to provide a tool of the character described which may be run into and removed from the well flow conductor by means of a flexible line running and pulling mechanism.

A still further object of the invention is to provide, in a device of the character described, means for positively retracting the anchoring means from engagement in the coupling recess of the flow conductor.

Still another object of the invention is to provide, in a device of the character described, means normally holding the locking means in inoperative position but adapted to be moved to permit said locking means to expand to locking position upon upward longitudinal movement of the rest of the tool with respect to said means.

Still a further object of the invention is to provide, in a device of the character described, releasable means preventing movement of the anchoring means to inoperative position, said means being releasable upon upward longitudinal movement of the well tool in the well flow conductor, whereby the anchoring means may be positively moved to retracted or inoperative position.

A particular object of the invention is to provide a well tool of the character described having anchoring means which are expanded to locking engagement in the coupling recess of the well flow conductor and are securely held in such locking position without frictional engagement between the mandrel of the well tool and the anchoring means.

2

Additional objects and advantages of the invention will readily be apparent from the reading of the following description of a device constructed in accordance with the invention, and reference to the accompanying drawings thereof, wherein:

Figure 1 is a view, partly in elevation and partly in section, of a well tool constructed in accordance with the invention and showing the same being lowered into a well flow conductor,

Figure 2 is a similar view showing the well tool in anchored position,

Figure 3 is a view, partly in elevation and partly in section, showing the well tool being removed from anchored position in the flow conductor,

Figure 4 is a horizontal cross-sectional view taken on the line 4—4 of Figure 1,

Figure 5 is a horizontal cross-sectional view taken on the line 5—5 of Figure 2, and

Figure 6 is a view of the upper end of a modified form of mandrel for the well tool.

In the drawings, the numeral 10 designates an elongate substantially cylindrical mandrel, having an enlarged section 11 at its upper end. The under side of the enlarged section is tapered inwardly and downwardly to form a substantially frusto-conical expander section 12, while the upper portion of the enlarged section is reduced in diameter and provided with an external annular flange 13 at its extreme upper end which serves as a retrieving connection, as will herein-after be explained.

A plurality of locking dogs 15 having substantially T-shaped lower ends 16 are slidable on the mandrel and each dog has its T-shaped end loosely confined within one of a plurality of inverted T-shaped slots 17 formed in the periphery of a carrier member or sleeve 18 which is slidable on the mandrel. The lower larger portion of each of the slots 17 is longitudinally larger than the cross piece at the lower end of the dog confined therein, whereby the dog may undergo a longitudinal movement within said slot.

An elongate retaining sleeve 19 telescopes the lower portion of the dogs and the carrier 18 and confines the lower ends of the dogs within the slots 17 between said sleeve and the mandrel.

The lower portion of the bore of the retaining sleeve 19 is reduced in diameter to form an upwardly facing shoulder 19a and is freely slidable on the lower portion of the mandrel. Outwardly bowed friction springs 20 have their upper ends secured to the lower end of the sleeve 19 and depend therefrom. The lower ends of the friction

springs are secured to a follower ring 21 which is also slidable on the mandrel and is prevented from sliding off the mandrel by a retaining nut 22 screw-threaded onto the lower end of said mandrel.

The dogs 15 are provided with large substantially rectangular outwardly extending bosses 25 at their upper ends, and have beveled surfaces 26 at their inner upper ends. Leaf springs 27 are attached to the rear surfaces of the dogs near their mid-portions and bow outwardly thereabove, whereby the upper ends of the dogs are normally urged outwardly from the mandrel toward the position illustrated in Figure 2.

A shear pin 28 extends transversely through the lower portion of the carrier member 18 and the mandrel 10 near the mid-portion of the mandrel, and this shear pin normally prevents longitudinal movement of the carrier member with respect to the mandrel, whereby the dogs are positioned adjacent the expander section 12 of the mandrel. Thus, when the dogs are in their lowermost position in the slots 17 they will not engage the expander section, but when said dogs are moved to their uppermost position in said slots they may be engaged by the expander section and expanded or moved radially outwardly to the position shown in Figure 2.

When the retaining sleeve 19 is in the upper position, shown in Figure 1, the internal shoulder 19a of the sleeve engages the lower end of the carrier member 18 to prevent further upward movement of the retaining sleeve. The large portion of the bore of the sleeve extends upwardly about the carrier member past the mid-portion of the locking dogs and, consequently, engages the outer surfaces of the dogs to hold the same in the retracted position illustrated in Figure 1, whereby the bosses 25 are held out of engagement with the wall of a well flow conductor C into which the device is adapted to be lowered. The friction springs 20 engage the inner wall of the conductor to maintain the retaining sleeve 19 in the upper position as the well tool is lowered into the bore of said conductor, whereby the dogs are maintained in retracted position during lowering.

However, when the well tool has reached the depth in the well conductor at which it is desired to be set or anchored, the mandrel of the well tool is raised while the friction springs 20 hold the retaining sleeve 19 substantially stationary as the mandrel moves upwardly. Thus, the dogs are engaged by the lower end of the slots in the carrier member 18 and are moved upwardly thereby with respect to the retaining sleeve. When the dogs have been moved upwardly until the lower ends of the leaf springs 27 are positioned above the upper end of the sleeve 19, the leaf springs will urge the upper ends of the dogs outwardly into engagement with the wall of the well pipe. Continued upward movement of the mandrel will lift the tool until the dog bosses 25 engage in a coupling recess 30 between the adjacent ends of two sections of the well flow conductor, whereupon the bosses will be expanded into such recess to stop upward movement of the well tool.

When the dog bosses have engaged in the coupling recess 30, the mandrel 10 is lowered until the frusto-conical expander section 12 thereon engages the beveled surfaces 26 at the inner upper end of the dogs to securely hold the dogs in expanded position with the bosses 25 engaged in the coupling recess. Therefore, any

well device which is lowered into the flow conductor and permitted to come to rest upon the upper end of the mandrel will be supported thereon against downward movement in the well flow conductor by engagement of the bosses with the upper end of the lower section of the well flow conductor.

The well tool is lowered into the flow conductor by means of a flexible steel line 31 having a lowering tool 32 connected to its lower end. The lowering tool has a depending cylindrical skirt which closely telescopes the flange 13 at the upper end of the mandrel and is releasably secured thereto by a shear pin 33 positioned in a transverse opening formed in said skirt and flange. When the dog bosses 25 have been expanded into the coupling recess in the manner just described, application of a downward force to the lowering tool will shear the pin 33 to release the lowering tool 20 from the mandrel, whereby the lowering tool may be raised out of the flow conductor.

When it is desired to remove the well tool from within the well flow conductor, a suitable retrieving tool 35, having resiliently mounted grab dogs 36 at its lower end, is lowered into the well flow conductor upon the flexible line lowering mechanism in the customary manner until the grab dogs 36 engage under the flange 13 at the upper end of the mandrel. The retrieving tool is then lifted to lift the mandrel until the frusto-conical section 12 is raised from engagement with the beveled surfaces 26 at the upper end of the dogs. Continued upward movement of the mandrel will cause the carrier member 18 to be moved upwardly until the lower end of the T-shaped slots 17 engage the lower end of the dogs to move the bosses 25 at the upper end of the dogs into engagement with the lower end of the upper section of the well flow conductor at the coupling recess. Such engagement prevents further upward movement of the dogs and the carrier member. A continued upward pull on the mandrel will then cause the shear pin 28 to be fractured to permit the carrier member 18 to move downwardly with respect to the mandrel until the carrier member and the lower ends of the dogs are moved downwardly within the retaining sleeve 19 to the position shown in Figure 3, whereby the dogs are retracted and the bosses 25 are moved out of engagement within the coupling recess 30.

With the parts in the position illustrated in Figure 3, the well tool may be raised completely out of the well flow conductor. Should the dogs again attempt to move upwardly out of the restraining sleeve, the engagement of the bosses on the dogs with the inner wall of the flow conductor will tend to move the dogs back downwardly within the retaining sleeve to cause the dogs to be retracted, whereby the dogs will not prevent upward movement of the well tool within the flow conductor.

Obviously, the mandrel 10 may be provided with a longitudinal axial bore (not shown) to permit flow or passage of fluid therethrough.

Also, the upper end of the mandrel may be provided with an upstanding screw-threaded pin 40 extending upwardly above the external flange 13, whereby the mandrel may be connected to the lower end of a well device, such as a perforator, or the like, if desired.

It is also manifest that the well tool will operate successfully with only one dog, though it is preferable that two or more be provided. With one dog, the outer periphery of the en-

larged portion 11 of the mandrel would engage one side of the inner wall of the well flow conductor while the boss on the dog would engage in the coupling recess 30 to prevent downward movement of the mandrel when the boss is expanded to such position.

From the foregoing, it will readily be seen that an improved well tool has been provided which is adapted to be lowered into a well flow conductor and anchored therein at a coupling recess to serve as a stop or support to prevent downward movement of other well devices supported thereon. The well tool is provided with anchoring dogs having bosses which engage in the recess at a coupling between the ends of adjacent sections of the well flow conductor, and are held in this expanded position by a frusto-conical expander section on the mandrel, such expansion being maintained without substantial frictional engagement between the mandrel and the inner beveled surfaces 26 of the dogs. Once the bosses on the dogs have been expanded into the coupling recess, a considerable force may be applied downwardly upon the mandrel, and such force will be transferred through the frusto-conical expander surface and the dog bosses to the upper end of the lower of two adjacent sections of the well flow conductor, whereby the well tool is positively held against downward displacement within said flow conductor.

It will also be seen that the device may readily be lowered into and raised upwardly out of a well flow conductor by means of a flexible line raising and lowering mechanism, expansion and retraction of the anchoring means on the tool being accomplished by longitudinal movement of the tool within the well flow conductor.

The foregoing description of the invention is explanatory only, and changes in the details of the construction illustrated may be made by those skilled in the art, within the scope of the appended claims, without departing from the spirit or intent of the invention.

What I claim and desire to secure by Letters Patent is:

1. A well tool adapted to be lowered into a well flow conductor having annular recesses therein between sections thereof and including, a mandrel having a downwardly facing inclined expanding shoulder thereon, anchoring means movably carried by the mandrel below the expander shoulder, resilient means between the anchoring means and mandrel normally urging said anchoring means toward expanded anchoring position, a retaining sleeve slidable on the mandrel initially telescoping the lower portion of the anchoring means and engaging and restraining said anchoring means in retracted position, friction members on said sleeve engaging the bore wall of the conductor for restraining movement of said sleeve to permit movement of the mandrel and anchoring means with respect to the retaining sleeve whereby the mandrel and anchoring means may be moved upwardly with respect to the sleeve to permit the anchoring means to be expanded by the resilient means into one of the annular recesses in the conductor, the mandrel then being movable downwardly to engage the expanding shoulder with the anchoring means to positively hold said anchoring means in engagement with the annular recess to anchor the mandrel against downward movement in the conductor, and a retaining nut on the lower end of the mandrel below the retaining sleeve and friction means for limiting downward

movement of said friction means and sleeve on the mandrel.

2. A well tool adapted to be lowered into a well flow conductor having annular recesses therein between sections thereof and including, a mandrel having a downwardly facing inclined expander shoulder thereon, anchoring means movably carried by the mandrel below the expander shoulder, a releasable connection between said anchoring means and mandrel initially limiting longitudinal movement of the anchoring means on the mandrel, resilient means between the anchoring means and mandrel normally urging said anchoring means toward expanded anchoring position, a retaining sleeve slidable on the mandrel below the anchoring means initially telescoping the lower portion of the anchoring means and engaging and restraining said anchoring means in retracted position, friction means on said sleeve engaging the bore wall of the conductor for restraining movement of said sleeve to permit movement of the mandrel and anchoring means with respect to the retaining sleeve whereby the mandrel and anchoring means may be moved upwardly with respect to the sleeve to permit the anchoring means to be expanded by the resilient means into one of the annular recesses in the conductor, the mandrel then being movable downwardly to engage the expander shoulder with the anchoring means to positively hold said anchoring means in engagement with the recess to anchor the mandrel against downward movement in the conductor, the releasable connection between the anchoring means and mandrel being releasable by application of an upward force to the mandrel while the anchoring means is engaged in the annular recess to permit the anchoring means to move downwardly with respect to the mandrel, a stop member on the mandrel below the retaining sleeve and friction means engageable with said friction means when the mandrel is moved upwardly to move the retaining sleeve upwardly to reengage said sleeve with the anchoring means upon upward movement of the mandrel with respect to said anchoring means after the releasable connection has been released, said sleeve retracting the anchoring means from the recess in the flow conductor whereby the well tool may be raised out of the flow conductor.
3. A well tool adapted to be lowered into a well flow conductor having annular recesses therein between sections thereof and including, an elongate substantially cylindrical mandrel, an enlarged downwardly facing inclined expander section carried by said mandrel, a carrier member movable on the mandrel below the expander section, shear means initially releasably restraining the carrier member against movement on the mandrel, anchoring dogs having a lost-motion connection with the carrier member so as to be movable longitudinally with respect to said carrier and the mandrel into and out of engagement with the expander section, resilient means on the dogs engaging the mandrel and normally urging said dogs toward expanded position, a retaining sleeve slidable on the mandrel below the carrier member and telescoping said carrier and the lower portion of the dogs for initially restraining the dogs against movement to an expanded position, friction springs connected with the retaining sleeve and frictionally engaging the inner wall of the flow conductor restraining movement of the retaining sleeve

whereby the mandrel may be moved with respect to the retaining sleeve, said sleeve being movable away from restraining position upon upward longitudinal movement of the mandrel and carrier with respect to said sleeve to permit the dogs to be expanded into a recess in the flow conductor by the resilient means and to be engaged and held in such position by the expander section of the mandrel so as to support the mandrel against downward movement, the mandrel being movable upwardly while the dogs are engaged in the recess to shear the shear means and permit the carrier and dogs to be moved downwardly of the mandrel, and a stop member on the mandrel engageable with the friction springs limiting downward movement of the friction springs and retaining sleeve on the mandrel whereby the sleeve is moved upwardly with the mandrel to telescope the lower portion of the dogs and retract said dogs from engagement in the recess in the conductor, whereupon the tool may be removed from the conductor.

4. A well tool adapted to be lowered into a well flow conductor having annular recesses therein between sections thereof and including, an elongate substantially cylindrical mandrel having a connecting member at its upper end adapted for connection with a flexible line raising and lowering mechanism, an enlarged downwardly facing inclined expander section on the upper portion of the mandrel, a carrier sleeve secured on the mandrel below the expander section, anchoring dogs having a lost-motion connection with the carrier sleeve so as to be movable longitudinally with respect to said carrier and the mandrel into and out of engagement with the expander section, bosses on the upper ends of the dogs, springs on the inner sides of the dogs below the bosses engaging the mandrel and urging the dog bosses toward expanded position, a retaining sleeve slidable on the mandrel below the carrier sleeve and telescoping said carrier sleeve and the lower portion of the dogs adjacent the springs for initially restraining the dogs against movement of the bosses to expanded position, friction springs connected with the retaining sleeve and frictionally engaging the inner wall of the flow conductor restraining movement of the retaining sleeve whereby the mandrel and carrier may be moved with respect to the retaining sleeve, said retaining sleeve being movable away from restraining position upon upward longitudinal movement of the mandrel and carrier with respect to said retaining sleeve to permit the springs on the dogs to expand the bosses into a recess in the flow conductor, the mandrel then being movable downwardly with respect to the dogs to engage the expander section of the mandrel with the upper ends of the dogs so as to hold the bosses expanded and support the mandrel against downward movement, and a stop member on the mandrel below the retaining sleeve engageable with the friction springs limiting downward movement of the friction springs and retaining sleeve on the mandrel.

5. A well tool adapted to be lowered into a well flow conductor having annular recesses therein between sections thereof and including, an elongate substantially cylindrical mandrel, an enlarged downwardly facing inclined expander section on the upper portion of the mandrel, a carrier sleeve movably mounted on the mandrel below the expander section, a shear member initially releasably securing the carrier sleeve on the mandrel against movement, anchoring dogs having a lost-motion connection with the carrier sleeve so as to be movable longitudinally with respect to said carrier and the mandrel into and out of engagement with the expander section, bosses on the upper ends of the dogs, springs on the inner sides of the dogs below the bosses engaging the mandrel and normally urging the dog bosses toward expanded position, a retaining sleeve slidable on the mandrel below the carrier sleeve and telescoping the carrier sleeve and the lower portion of the dogs adjacent the springs for initially restraining the dogs against movement of the bosses to expanded position, friction springs connected with the lower end of the retaining sleeve and frictionally engaging the inner wall of the flow conductor restraining movement of the retaining sleeve whereby the mandrel and carrier may be moved with respect to the retaining sleeve, said retaining sleeve being movable downwardly with respect to the dogs upon upward longitudinal movement of the mandrel and carrier with respect to said retaining sleeve to permit the springs on the dogs to expand the bosses into a recess in the flow conductor, the mandrel then being movable downwardly with respect to the dogs to engage the expander section of the mandrel with the upper ends of the dogs so as to hold the bosses expanded and support the mandrel against downward movement, the mandrel being movable upwardly while the dog bosses are engaged in the recess to shear the shear member and permit the carrier sleeve and dogs to be moved downwardly of the mandrel, and a stop member on the mandrel below the retaining sleeve engageable with the friction springs to limit downward movement of the retaining sleeve on the mandrel and to move the retaining sleeve upwardly with respect to the dogs and carrier sleeve after the shear member has been sheared, whereby the retaining sleeve telescopes the lower portion of the dogs adjacent the springs to retract the dog bosses from the recess in the conductor so the tool may be removed from the conductor.
